PUMP VALVE

Joseph H. Butler, Tyler, Tex., assignor of one-half
to Dan R. Boisseau, San Antonio, Tex.

Application June 27, 1939, Serial No. 281,463

1 Claim. (Cl. 103—225)

This invention appertains to new and useful improvements in valve structures and more particularly to a pump valve such as is used in oil well pumps.

5 The principal object of the present invention is to provide a valve structure of the character stated which in operation will crush and pulverize sand to the end that the existence of sand in the pump cannot be detrimental to its proper 10 operation.

Another important object of the invention is to provide a valve which is positive acting and susceptible to only a minimum amount of wear, and which in use requires only infrequent repairs 15 and replacements.

These and other objects and advantages of the invention will become apparent to the reader of the following specification.

In the drawing:

20 Figure 1 is a side elevational view of the valve.
Figure 2 is a side elevational view partly in section.

Figure 3 is a perspective view of the packing sleeve.

25 Figure 4 is a plan view of the bottom cap showing the valve seat.

Referring to the drawing wherein like numerals designate like parts, it can be seen that the valve assembly consists of a barrel 5 having a head portion 6 through the upper tapered portion of which ports 7 are formed and from the upper end of which the threaded shank 8 extends. This, of course, connects to the usual pump rod. The barrel 5 where it merges with 30 the head 6 defines the shoulder 9 which acts as a stop for the slide collar 10 to prevent wear on the split sleeve 11.

This sleeve 11 which is provided with a wear-resisting metallic liner 12 is split longitudinally 40 as shown in Figure 1 and each end portion is provided with a tongue 13 which interlaps the complementary end portion by being disposed into a corresponding recess 14 therein.

The lower end of the barrel 5 is formed with 45 external threads for accommodating the internally threaded bottom cap 15. The side wall of this bottom cap 15 is formed with vertically extending ducts 16 opening through the upper beveled seat forming upper edge 17 and through the bottom of the cap 15 as is clearly shown in Figures 2 and 4 of the drawing.

50 Numeral 18 denotes the annular valve element which is provided with a beveled bottom face to match the beveled seat 17. When the cap 15

is fully screwed on to the lower end of the barrel 5, as can be seen in Figure 2, the valve seat face 17 will be substantially opposed to the ports 19 in the barrel 5, just above the threaded lower portion thereof.

5 An apertured lug 20 is provided on the bottom of the cap 15.

Ports 21 are formed in the side of the barrel 5 in opposed relation to the sleeve 11 and the purpose of these ports 21 is to allow the pressure of 10 the oil to exert itself against the packing sleeve 11 to expand the packing sleeve against the inside of the working barrel (not shown) to the end that sand and other foreign matter will be thoroughly pulverized.

15 Obviously, the collar 10, the packing sleeve 11 and the valve element 18 are free to slide up and down on the barrel 5.

It can be seen that on the down stroke of the valve assembly the collar 10, sleeve 11 and valve 20 element 18 will rise on the barrel 5, permitting oil to pass from the duct 16 through the ports 19 to the interior of the barrel 5 and out of the barrel head 6 by way of the ports 7.

25 On the up-stroke, to perform the lifting action of the oil thus captured, it can be seen that due to the frictional engagement of the sleeve 11 against the inside of the working barrel, the barrel 5 as it is lifted will move upwardly resulting in the engagement of the seat 17 against 30 the tapered valve element 18, thus cutting off the oil from below the barrel 5 so that further lifting of the barrel 5 and in fact the entire valve assembly will result in lifting the column of oil 35 above the valve assembly.

While the foregoing specification sets forth the invention in specific terms, it is to be understood that numerous changes in the shape, size and materials may be resorted to without departing from the spirit and scope of the invention as claimed hereinafter.

40 Having described the invention, what is claimed as new is:

A pump valve assembly comprising a barrel threaded at its lower end and provided with an 45 enlarged head at its opposite end defining a stop shoulder, a rod line attaching shank on the head, said head being hollow and in communication with the barrel and formed with outlet openings at the upper end thereof, an extensible sleeve 50 on the barrel and longitudinally slideable thereon, a ring on the barrel at the lower end of the sleeve and being slideable on the barrel, the ring being formed with an external bevel, an internally threaded cap for disposition over the lower 55

threaded end of the barrel and formed with an internal bevel at its upper edge defining a seat against which the beveled surface of the ring is seatable, said cap being formed with vertically extending ducts in the side wall thereof extending from the bottom of the cap and opening

through the seat, said barrel being formed with ports immediately opposed to the said seat and being closed by the ring when the barrel is moved in an upward direction.
